William Hanson Minnix

UNITED STATES PATENT OFFICE.

WILLIAM HANSON MINNIX, OF WASHINGTON, DISTRICT OF COLUMBIA.

DESIGN FOR A HANDKERCHIEF OR BANNER.

SPECIFICATION, forming part of Design No. 18,531, dated August 14, 1888.

Application filed July 12, 1888. Serial No. 279,785. Term of patent 3½ years.

To all whom it may concern:

Be it known that I, WILLIAM HANSON MINNIX, residing at Washington, District of Columbia, have produced a new and original Design for Handkerchiefs or Banners, of which the following is a specification, reference being had to the annexed drawing, forming part thereof, which represents my new design.

My design is specially adapted for that style of handkerchief called "bandanas;" but its use may be extended to other kinds of handkerchiefs or banners.

My design comprises a handkerchief or banner, A, in the field A' of which is a representation of a pair of pantaloons and a mercantile ship or vessel with its prow slightly entered into a pocket of the pantaloons. This representation may be placed upon any part of the field A' of the handkerchief or banner, and in

connection therewith I contemplate employing any suitable explanatory words. I also may use this representation in connection with other symbols or figures, as fancy may suggest; but such words, symbols, shape, texture, or exact configuration of the handkerchief other than by placing upon the field the representation described and shown forms no part of my design.

What I claim is—

The within design for a handkerchief or banner, comprising, mainly, a mercantile ship or vessel with its prow slightly entered into a pocket of a pair of pantaloons, as set forth.

WILLIAM HANSON MINNIX.
